UNITED STATES PATENT OFFICE.

DAVIS ZAIDEN, OF NEW YORK, N. Y., ASSIGNOR TO ANNA ZAIDEN, OF NEW YORK, N. Y.

NECKTIE-SECURING DEVICE.

No. 895,322.

Specification of Letters Patent.

Patented Aug. 4, 1908.

Application filed March 9, 1908. Serial No. 419,905.

To all whom it may concern:

Be it known that I, DAVIS ZAIDEN, a subject of the Emperor of Russia, and resident of New York city, State of New York, have 5 invented certain new and useful Improvements in Necktie-Securing Devices, of which the following is a specification.

The object of my invention is to provide a necktie securing device, comprising a collar-button of a new and improved form, which when once in position will not rotate in the button-hole of the shirt; and to provide a plate which may be secured upon the inner side of a necktie, and adapted to be secured 15 upon the said collar-button quickly and instantaneously, and as quickly removed.

To such ends my invention consists in substance, of a collar-button having a shank of ellipsoidal form in cross-section, having an 20 enlarged head of substantially the same ellipsoidal-conical form on the outer face and square shouldered at the inner where it is joined to the shank; and of a securing plate having a back-plate provided with a button- 25 head-receiving cavity which securing-plate is provided with two securing spring members, provided with press-lugs projecting from the same for throwing the same into the releasing position, by which such collar-but- 30 ton and plate may be secured together, and prevented from turning one upon the other.

My said invention is fully shown and described in the following specification, of which the accompanying drawing forms a 35 part, wherein similar numerals of reference designate like or equivalent parts wherever found throughout the several views, and in which:—

Figure 1 is a side view of my improved 40 necktie securing device taken in central vertical section, the bow or tie to be carried by the securing plate thereof not being shown. Fig. 2 is a view in detail of the button, and Fig. 3 a detail view from the back of the 45 double securing-plate. Fig. 4 is a detail view from the back of the securing-plate with the back-plate thereof removed, showing the interior mechanism; and Fig. 5 is a detail view from the back of the back-plate 50 of the securing-plate.

Referring to the drawing:—The button of my improved necktie securing device is usually formed of one piece of metal struck up into the required form in any desired 55 manner, and comprises a base-plate 1, a shank 2 and a head 3. Both the shank and

head are of ellipsoidal form, and the head is conical ellipsoidal on the front edge, but is provided with a plane rear-face 5. The ellipsoidal form of the head facilitates passage of 60 the same through the button-hole and the like form of the shank prevents turning of the same when once placed therein.

The securing-plate 6 consists of a metallic box struck up of thin metal so as to form the 65 face-plate 7, the side walls 8 of which are provided with slip-sockets 9, to receive the press-lugs 10 of the securing spring-clips 11, and such face-plate is provided, preferably at the corners, with orifices 12, by which the 70 same may be secured by sewing to the necktie desired to be secured in position thereby; and with the central button orifice 13 of the same shape and size as is the securing-head 3 of the button. The securing clips are 75 struck up out of suitable resilient sheet metal having the press-lugs 10, the spring-fingers 15, and the button-securing-fingers 17. These spring-clips are placed in position in the box portion of the securing-plate 80 6, as shown in detail in Fig. 4, with the press-lugs 10 thereof extending out through the slip-sockets 9, formed to receive the same, through the side walls 8 of such plate, as shown in detail in Figs. 1 and 4, and locked 85 in position by a back-plate 16, usually of the form shown; which is cut away at the corners as shown at 17 so as to permit of the securing-plate being sewed to the necktie, and being provided with a dished button-head- 90 cavity 18* at the center to receive the head 3 of the button. The securing spring-clips 11 having been placed in position in the box of the securing-plate 6, the back-plate 16 is placed thereon, and secured in position in 95 any desired manner, usually by turning down over the same small securing lugs 18 formed integral with the end walls of the face-plate, as shown in Figs. 1 and 3, and thus formed the securing-plate 6 is fastened by sewing or 100 in any other desired manner to the tie; when the button having been inserted in the button-hole of the shirt of the wearer, the tie bearing the plate 6 may be secured in position, by merely pressing the same upon the button, as the spring-clips will yield as the head 105 3 of the button is pressed against them, in such manner as to allow such head to pass by such clips, until by their own resiliency, they fall behind the plane rear face 5 of the 110 head 3, and thus lock such button and securing-plate securely together; until such time

as manual pressure shall be exerted upon the press-lugs 10, when the tie can of course be instantaneously removed, and it will be seen that as the ellipsoidal head of the button fits snugly in the like shaped cavity of the back-plate of the securing-plate, this will prevent rotation of the plate upon the button.

The provision of the button-hole socket 18^x, which conforms to the peculiar shape of my button-head, is important and performs a useful function, in that it insures that the button shall be held against rotation. It is true that the spring-fingers 11', 11' and the shape of the button-shank tend to secure the button against rotation, but the button-head socket 18^x holds the button against rotation more firmly.

What I claim is:—

1. In a device of the class described, a button having a shank of larger diameter in cross section one way than another and a head also of larger diameter in cross section one way than another; a plate adapted to be secured to a tie and through which said button projects, said plate having means removably locking the plate to the button; and a back-plate carried by said first-mentioned plate and having a socket of similar shape to the button head, and within which 30 socket the button-head rests in use.

2. In a device of the class described, a button having an enlarged head, a securing-plate having a central orifice for the recep-

tion of said head, and securing-clips having press-lugs and curved spring-fingers surrounding and clasping the button-shank back of the head, said securing-clips, press-lugs, and spring-fingers being in one integral piece.

3. In a device of the class described, a button having an enlarged head, a securing-plate formed with a surrounding vertical flange and with a central orifice for the passage of the head, and two securing-clips resting on the plate and formed of spring material, and having, at their lower extremities, tails bearing against the inner surface of said flange, and having, also, at their upper extremities, curved fingers surrounding and clasping the button-shank in the rear of the 50 enlarged head.

4. In a device of the class described, a button having an enlarged head, a securing-plate having a central orifice for the reception of the enlarged head, securing-clips having press-lugs spring-fingers and securing-fingers carried by the securing-plate, and a back-plate to the securing-plate securing the securing clips in position, and provided with a central cavity to receive the enlarged head 60 of the button so as to secure the same against rotation in the securing-plate.

DAVIS ZAIDEN.
